UNITED STATES PATENT OFFICE.

ULRICH EBERHARDT, OF NEWARK, NEW JERSEY.

DESIGN FOR A FRAME FOR BARREL-SCRUBBING MACHINES.

SPECIFICATION forming part of Design No. 22,361, dated April 18, 1893.

Application filed November 9, 1892. Serial No. 451,468. Term of patent 14 years.

To all whom it may concern:

Be it known that I, ULRICH EBERHARDT, a citizen of the United States, residing at Newark, Essex county, New Jersey, have invented 5 a certain new and useful Design for a Barrel-Scrubbing-Machine Frame, fully described and represented in the following specification and the accompanying drawings, forming a part of the same.

This design consists in the shape herein shown and described for the frame of a barrel scrubbing machine.

In the annexed drawings, Figure 1 is an end elevation, and Fig. 2 a side elevation of a 5 machine frame embodying my design.

The end stanchions are of columnar form; the upper portion A' having a central oblong opening with parallel sides, the base l being forked to form an arch below the body por-

tion A, which latter is provided with two lateral projections d and an intermediate open rectangular recess e upon each of its opposite edges nearly even with the lower end of the opening in the portion A'. The stanchions are connected by an upper-tie beam shaped 20 like an inverted T, with straight stem H and arched cross bar G, and the lower tie-beams C. 25

Having thus described the design, what I claim is—

The design for a barrel scrubbing machine 30 frame herein shown and described.

In testimony whereof I have hereunto set my hand in the presence of two subscribing witnesses.

ULRICH EBERHARDT.

Witnesses:

F. L. EBERHARDT,
THOMAS S. CRANE.
